HAT FASTENER

Lena Sreden, New York, N. Y., assignor, by direct and mesne assignments, of one-half to Equality Novelty Corp., New York, N. Y., a corporation of New York, and one-half to Jack I. Ellerstein-Chas. A. Gerber Corp., New York, N. Y., a corporation of New York

Application February 9, 1940, Serial No. 318,076

5 Claims. (Cl. 132—59)

This invention relates to new and useful improvements in a hat fastener.

More specifically, the invention proposes the construction of a hat fastener characterized by an elastic band having its ends provided with a novel means for attaching the same to the lining, or sweatband of a hat in a manner to be extended across the rear of one's head to hold a hat securely in position upon the head.

Still further it is proposed to characterize said means by a sheet metal strip, for each end of the band, having a bent edge portion adjacent the end of the band, and front and rear portions continuing from said bent edge portion in a manner to be adapted to be clamped upon the front and rear faces of the end portion of the band.

Still further it is proposed to provide the free ends of the front and rear portions of the strip with elements for engaging the faces of the band to frictionally and securely hold the strip in position thereon.

Still further it is proposed to provide the strip with a pair of bendable piercing elements which are adapted to be engaged through the sweatband or lining or other part of the hat in a manner to attach the ends of the band to the hat.

Another object of this invention is to so construct the bendable piercing elements that in addition to securing the ends of the band to the hat they will act to securely lock the sheet metal strips in position upon the ends of the band.

For further comprehension of the invention, and of the objects and advantages thereof, reference will be had to the following description and accompanying drawing, and to the appended claims in which the various novel features of the invention are more particularly set forth.

Fig. 1 is a perspective view of the hat fastener constructed in accordance to this invention.

Fig. 2 is a perspective view of one of the sheet metal strips per se used in the hat fastener and illustrated in its open position.

Fig. 3 is a fragmentary elevational view of one end of a band constructed in accordance with a modification of the invention.

Fig. 4 is a top view looking in the direction of the line 4—4 of Fig. 3.

Fig. 5 is a horizontal sectional view of one of the sheet metal strips used in connection with the modification of the invention shown in Fig. 3, and illustrated in its open position before being applied to the end of the band.

Fig. 6 is a fragmentary elevational view similar to Fig. 3, but illustrating a modification of the invention.

Fig. 7 is a perspective view of the sheet metal strip illustrated in an open condition, used in connection with the form of the invention shown in Fig. 6.

Fig. 8 is a perspective view of one end of a band constructed in accordance with a still further modification of the invention.

Fig. 9 is a view similar to Fig. 8 but illustrating still another modification of the invention.

The hat fastener, according to this invention, includes a band 10. This band 10 is preferably constructed of elastic material and is provided with a plurality of vertically extending pleats 10a, or folds or corrugations which are maintained in positions by means of parallel rows of stretchable stitches 11 extending along the length of the band 10.

A sheet metal strip 12 is provided for each end of the band 10 and has a bent edge portion 12a laying immediately adjacent its respective end of the band 10. This bent edge portion continues into a front portion 12b and a rear portion 12c which extend along the front and rear faces of the end portion of the band 10. These front and rear portions are adapted to be clamped into face contact with the faces on the end portion of the band 10. The front portion 12b and the rear portion 12c are further provided with elements for gripping and engaging the band for frictionally and securely holding, or otherwise holding, the strip 12 in position upon the end of the band. The front portion 12b is provided with an inturned edge element 12bb which is adapted to engage and grip the front face of the band 10. The rear portion 12c is provided with a plurality of inwardly extending teeth elements 12cc which are adapted to engage and grip the rear face of the band 10 and cooperate with the inturned element 12bb in securely holding the strip in position.

One of the portions of the strip 12, preferably the front portion 12b, is provided with a pair of bendable piercing elements 13 which are adapted to be engaged through the sweatband or lining, or other portion of a hat in a manner to securely attach the ends of the band to the hat. These bendable piercing elements 13 are preferably in the form of prongs stamped from the material of the front portion 12b and which are provided with pointed ends for facilitating the engagement of the same through the sweatband or lining and which are adapted to be bent over to clamp the lining or sweatband against the face of the portion 12b.

The operation of this form of the invention is as follows:

The hat fastener is used in the condition as shown in Fig. 1, and the ends thereof are adapted to be attached to oppositely disposed sides of a hat by engaging the piercing elements 13 through the lining, or sweatband or other part of a hat, whereupon they are adapted to be bent over to securely hold the ends of the band in position upon the hat. The hat is then engaged upon one's head in the conventional manner and the band 10 is extended across the back of the head in a manner to securely hold the hat in position thereon.

According to the modification of the invention shown in Figs. 3 to 5 inclusive, the construction of the hat fastener is similar to that previously described, except that the bendable piercing elements 13a are stamped from the rear portion 12c of the sheet metal strip 12, and in addition to securing the band 10 to the hat, these piercing elements 13a act to securely lock the sheet metal strip 12 in position upon the end of the band. The piercing elements 13a, as previously described, are arranged substantially in a horizontal plane and stamped from the rear portion 12c. These piercing elements 13a are passed through the end portion of the band 10 and through aligned openings 14 formed in the front portion 12b of the strip 12. These piercing elements 13a are further provided with inwardly extending cutouts 15 which are in an aligned position with the openings 14 for permitting a slight twist to be imparted to the piercing elements 13a, as shown in Fig. 3, for causing the shoulders formed by the cutouts 15 to engage the front face of the front portion 12b to securely hold the sheet metal strip 12 in position upon the end of the band 10.

As shown in Fig. 4 the pointed ends of the piercing elements 13a are free and are adapted to be engaged through the lining, or sweatband of a hat as previously described for securing the ends of the band 10 to the hat. In other respects this form of the invention is similar to the previous form and like parts may be identified by corresponding reference numerals.

In the modification of the invention shown in Figs. 6 and 7 the construction of the hat fastener is similar to that described relative to Figs. 3-5, except that the piercing elements 13b are arranged in a vertical plane instead of a horizontal plane, and are cooperative with openings 14, and are formed with cutouts 15 for permitting the piercing elements 13b to be used for locking the sheet metal strips in position upon the ends of the band 10 in addition to securing the ends of the band to the hat. In other respects this form of the invention is similar to the previous forms.

In the form of the invention shown in Fig. 8 the piercing elements are in the form of a U-shaped wire 16 having the junction 16a of its arms 16b disposed between the adjacent sides of the bent edge portion 12a of the strip 12 and the end of the band 10. This junction 16a is rotatively held in position. The arms 16b are provided with points which are adapted to be passed through the lining, or sweatband of a hat, and the arms are adapted to be bent for securely attaching the ends of the band to the hat.

According to the modification of the invention shown in Fig. 9 the construction of the hat fastener is characterized by the fact that the

arms 16bb of the U-shaped wire 16' are bent into the shape of hooks for engaging the lining or sweatband of a hat. In other respects this form of the invention is similar to the previous forms and similar parts may be identified by corresponding reference numerals.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a hat fastener having a band, means for attaching one end of said band to a sweatband or lining of a hat, comprising a sheet metal strip having a bent edge portion for location adjacent one end of said band and having front and rear portions continuing from said bent edge portion for engaging over the front and rear faces of the end portion of said band, gripping elements on said front and rear portions of said strip for engaging said band for securely holding the strip on the band, and a pair of bendable piercing elements stamped from one of said portions and projecting at right angles thereto and adapted to be engaged through the sweatband or lining or other part of a hat to hold the band attached on the hat.

2. In a hat fastener having a band, means for attaching one end of said band to a sweatband or lining of a hat, comprising a sheet metal strip having a bent edge portion for location adjacent one end of said band and having front and rear portions continuing from said bent edge portion for engaging over the front and rear faces of the end portion of said band, gripping elements on said front and rear portions of said strip for engaging said band for securely holding the strip on the band, and a pair of bendable piercing elements stamped from one of said portions and projecting at right angles thereto and adapted to be engaged through the sweatband or lining or other part of a hat to hold the band attached on the hat, said gripping elements comprising an inturned edge on one of said portions and cooperative gripping teeth on the other of said portions for engaging the faces of the end portion of the band.

3. In a hat fastener having a band, means for attaching one end of said band to a sweatband or lining of a hat, comprising a sheet metal strip having a bent edge portion for location adjacent one end of said band and having front and rear portions continuing from said bent edge portion for engaging over the front and rear faces of the end portion of said band, gripping elements on said front and rear portions of said strip for engaging said band for securely holding the strip on the band, and a pair of bendable piercing elements mounted on said strip and adapted to be engaged through the sweatband or lining or other part of a hat to hold the band attached on the hat, said bendable piercing elements comprising prongs stamped from the rear portion of said strip for engagement through the end portion of said band and engaging through complementary aligned openings formed in the front portion of said strip, and means for locking said prongs and said front portion of said strip together.

4. In a hat fastener having a band, means for

attaching one end of said band to a sweatband or lining of a hat, comprising a sheet metal strip having a bent edge portion for location adjacent one end of said band and having front and rear portions continuing from said bent edge portion for engaging over the front and rear faces of the end portion of said band, gripping elements on said front and rear portions of said strip for engaging said band for securely holding the strip on the band, and a pair of bendable piercing elements mounted on said strip and adapted to be engaged through the sweatband or lining or other part of a hat to hold the band attached on the hat, said bendable piercing elements comprising prongs stamped from the rear portion of said strip for engagement through the end portion of said band and engaging through complementary aligned openings formed in the front portion of said strip, and means for locking said prongs and said front portion of said strip together, said means comprising cutouts formed on said prongs and in aligned position with said openings and having shoulders engaging the front face of the front portion of said strip.

5. In a hat fastener having a band, means for attaching one end of said band to a sweatband

or lining of a hat, comprising a sheet metal strip having a bent edge portion for location adjacent one end of said band and having front and rear portions continuing from said bent edge portion for engaging over the front and rear faces of the end portion of said band, gripping elements on said front and rear portions of said strip for engaging said band for securely holding the strip on the band, and a pair of bendable piercing elements mounted on said strip and adapted to be engaged through the sweatband or lining or other part of a hat to hold the band attached on the hat, said bendable piercing elements comprising prongs stamped from the rear portion of said strip for engagement through the end portion of said band and engaging through complementary aligned openings formed in the front portion of said strip, and means for causing said prongs to lock said strip in position upon the end portion of said band, said means comprising cutouts formed on said prongs and in aligned position with said openings and having shoulders engaging the front face of the front portion of said strip, said prongs being extended along the horizontal.

LENA SREDEN.
